CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,122,232.

Specification of Letters Patent. Patented Dec. 22, 1914.

Application filed May 24, 1912. Serial No. 699,370.

To all whom it may concern:

Be it known that I, CORMELIUS B. CORCORAN, a citizen of the United States, residing in borough of Bronx, city of New York, 5 in the county of New York and State of New York, have invented certain new and useful Improvements in Type-Writing Machines, of which the following is a specification.

10 This invention relates to typewriting machines, and more particularly to line-spacing mechanisms wherein the platen may be released from the line-space wheel and adjusted relatively thereto so as to move the 15 paper a fraction of a full line-space.

The principal object of this invention is 20 to provide between the platen and the line-space wheel, a connection which will permit any desired adjustment of the platen relatively to the line-space wheel, which connection in every position of adjustment is firm enough to prevent accidental slip between these parts in the normal operation of the 25 machine, the connection being also neat in appearance and easily applicable to existing types of machines.

The line-space wheel is loose upon the 30 axle and may have rigidly connected thereto an internal or annular gear meshing with a pinion mounted upon an arm pivoted on a plate connected to the platen. Mounted on this plate may be a pair of toggles carrying a clutch shoe adapted to frictionally engage the grooved periphery of a disk fixed to the 35 pinion. A wedge may be between the joints of the toggles, which wedge is normally forced in by a spring to keep the clutch shoe tightly in contact with the grooved disk, thereby also forcing the pinion firmly 40 into mesh with the annular gear, thus eliminating any lost motion which might arise between the pinion and gear. Moreover, any force exerted on the platen to rotate the same relatively to the line-space wheel, and 45 hence to rotate the pinion about the axis, also tends to increase the toggle effect so as to force the clutch shoe still more firmly into engagement with the grooved disk.

Other features and advantages will hereinafter appear.

In the accompanying drawings, Figure 1 is a fragmentary perspective view of the line-space mechanism of an Underwood writing machine with the present invention 55 applied thereto. Fig. 2 is a sectional end

view, partly broken away, illustrating the position of the parts when the clutch is set. Fig. 3 is a view similar to Fig. 2, illustrating the position of parts when the clutch is released. Fig. 4 is a sectional elevation 60 illustrating the clutch operating device forced outward in position to set the clutch. Fig. 5 is a view similar to Fig. 4, illustrating the clutch operating device forced inward into position to release the 65 clutch. Fig. 6 is a detail perspective view illustrating the various parts of the clutch mechanism detached from each other.

The usual line-space operating lever 1 is mounted on the carriage 2 of a typewriting 70 machine and actuates a bar 3 carrying a pawl 4 engaging the teeth 5 of line-space wheel 6 on the platen axle 7 upon which is fixed the platen 8. Detent 9 engaging the teeth of the line-space wheel holds the latter in adjusted position, for the ordinary line-spacing. All of this mechanism is found in the usual type of Underwood writing machine.

The line-space wheel 6 is loose upon the 80 axle 7 and is clutched to and unclutched therefrom as follows: Projecting outward from the platen turning knob 10 is a finger-piece 11, held outwardly by a spring 12 seated in a recess 13 of the hub or sleeve 85 14 of the knob. Connected to finger-piece 11 is a pair of rods 15 passing freely through apertures 16 formed in the knob. At their inner ends these rods are secured 90 to a collar 17 secured to a sleeve 18 slidably mounted on the platen axle. The inner end of this sleeve is formed into a wedge 19 having outwardly inclined faces 19^a passing through an opening 21 formed in a plate 20 fixed to the platen shaft. Pivoted on plate 20 is a pair of arms 22 having pivoted thereto another pair of arms 23 carrying at their extremities a wedge faced clutch shoe 24 adapted to be thrown into and out of engagement with a peripherally grooved brake wheel or disk 25. The latter is fixed to a pinion 26 mounted on a pair of arms 27 pivoted to plate 20. This pinion meshes with an internal or annular gear 28 integral with or otherwise 105 secured to the line-space wheel. A spring 29 is provided which forces the arms 27 outward, thus normally holding the pinion yieldably in mesh with the annular gear.

It will be seen that the arms 22 and 23 110

form a pair of toggles which are engaged adjacent their knees by the inclined faces 19^a of the wedge 19. The spring 12 normally holds the finger-piece 11 outward, 5 thus forcing the inclined faces 19^a of the wedge into engagement with the toggles, tending to straighten them out and to force the clutch shoe 24 firmly into engagement with the grooved disk. The pinion 26 is 10 thus held from rotation about its axis, and is brought tightly into mesh with the teeth of the annular gear 28. The annular gear in its motion then carries with it the plate 20, axle 7, and platen 8 fixed thereto. The 15 gear 28 thus forms a driving member operating through the driven member or pinion 26 to rotate the platen as a unit with the line-space wheel. By reason of the tight mesh between the annular gear and pinion, 20 all lost motion between these members is avoided, and the platen is thus held rigidly to the line space wheel. When the operator desires to disengage the platen from the line-space wheel and to turn the platen a 25 fraction of a full-line space, he grasps the platen turning knob forcing inward the finger-piece 11, and through the connections above described releasing the pinion from the clutch shoe. The platen turning knob 30 may then be rotated so as to turn the platen to any desired position. When finger-piece 11 is released, spring 12 automatically resets the clutch. It may be noted that when the clutch is set, any force tending to rotate 35 the pinion about its axis tends also to move the clutch shoe and to swing arms 23, thus giving rise to a toggle action tending to force the shoe still more firmly into engagement with the grooved disk. Suitable 40 means is provided for guiding the toggles and clutch shoe so as to maintain them in alinement with the grooved disk and to take up the thrust of the wedge. This means consists of a plate 30 straddling the platen 45 axle and fastened to plate 20 at any suitable point as to bosses 31 and 32 projecting therefrom, to the latter of which bosses arms 27 are also pivoted.

A cup 33 may be provided to inclose the 50 parts of the clutch mechanism. This cup may be attached in any suitable manner to the line-space wheel, as by being threaded or screwed to the extension of the annular gear.

55 Variations may be resorted to within the scope of the invention, and portions of the improvements may be used without others.

Certain of the features herein disclosed are claimed in application No. 637,049, filed 60 July 6, 1911, including the large gear, the pinion in mesh therewith, and means for preventing rotation of the pinion upon its own axis, thereby locking the line-space wheel and platen together; and in application No. 772,545, which is a division of

637,049, there is claimed broadly a friction device connected to the pinion for frictionally preventing the rotation of the pinion upon its own axis, and thereby locking the line-space wheel and platen together; both 70 of said applications claiming means operative at any part of the revolution of the platen for releasing the pinion to permit its rotation, and thereby allow adjustment of the platen relatively to the line-space 75 wheel.

Having thus described my invention, I claim:

1. In a typewriting machine, a platen, a line-space wheel, a gear secured to said wheel, a pinion mounted so as to be movable into positions to tightly or loosely mesh with the gear, said pinion being connected to the platen shaft, and means movable into and out of braking connection with said pinion, 80 said means also moving said pinion bodily into tight mesh with said gear.

2. In a typewriting machine, a platen, a line-space wheel, a gear secured to said wheel, a pinion meshing with the gear, a 85 brake wheel or disk secured to the pinion, a clutch shoe movable into and out of engagement with the brake disk, and toggle mechanism for actuating the shoe.

3. In a typewriting machine, a platen, a 90 line-space wheel, a gear secured to said wheel, a pinion meshing with the gear, a 95 brake wheel or disk secured to the pinion, a clutch shoe movable into and out of engagement with the brake disk, a toggle for actuating the shoe, and a wedge for operating the toggle.

4. In a typewriting machine, a platen, a line-space wheel, a gear secured to said wheel, a pinion mounted so as to be movable 100 into positions to tightly or loosely mesh with the gear, said pinion being connected to the platen shaft, means movable into and out of braking connection with said pinion, said means also moving said pinion bodily into 105 tight mesh with said gear, and a spring for operating said means.

5. In a typewriting machine, a platen axle, a line-space wheel, a gear secured to said wheel, a pinion meshing with said gear, a 110 support for said pinion, said support being movable transversely to the platen axle, a clutch shoe movable into and out of connection with the pinion, and toggle mechanism for actuating the shoe.

6. In a typewriting machine, a platen axle, a line-space wheel, a gear secured to said wheel, a pinion meshing with said gear, a support for said pinion, said support being 115 movable transversely to the platen axle, a clutch shoe movable into and out of connection with the pinion, toggle mechanism for actuating the shoe, and a wedge for operating the toggle.

7. In a typewriting machine, a platen axle, 120

a line-space wheel, a gear secured to said wheel, a pinion meshing with said gear, a support for said pinion, said support being movable transversely to the platen axle, a clutch shoe movable into and out of connection with the pinion, and a pair of toggles for actuating the shoe, the latter being mounted on said toggles.

8. In a typewriting machine, a platen axle, a line-space wheel, an internally toothed gear secured to said wheel, a pinion meshing with said gear, a support for said pinion, said support being movable transversely to the platen axle, a clutch shoe movable into and out of connection with the pinion, a pair of toggles for actuating the shoe, and a wedge for spreading said toggles.
10. In a typewriting machine, the combination of a platen, a line-space wheel, a gear secured to said wheel, a pinion meshing with said gear, a support for said pinion, said support being movable transversely to the platen, a clutch shoe movable into and out of connection with the pinion, a pair of toggles for actuating the shoe, and a wedge for spreading said toggles.

9. In a typewriting machine, the combination of a platen, a line-space wheel, a gear secured to said wheel, a pinion meshing with said gear, a support for said pinion, said support being movable transversely to the platen, a clutch shoe movable into and out of connection with the pinion, a pair of toggles for actuating the shoe, and a wedge for spreading said toggles.
15. In a typewriting machine, the combination of a platen, a line-space wheel, a gear secured to said wheel, a pinion meshing with said gear, a support for said pinion, said support being movable transversely to the platen, a clutch shoe movable into and out of connection with the pinion, a pair of toggles for actuating the shoe, and a wedge for spreading said toggles.

10. In a typewriting machine, a platen axle, a line-space wheel, an annular gear secured to said wheel, a plate secured to the axle adjacent to the wheel, arms pivoted on said plate, a pinion rotatably mounted in said arms and meshing with said gear, a pair of toggles mounted on said plate, a clutch shoe carried by said toggles, a wedge passing through said plate and engaging said toggles, a platen rotating knob secured to the platen axle, and means projecting outwardly from said knob, and connected to said wedge for operating the same.

40. 11. In a typewriting machine, a platen axle, a line-space wheel, an annular gear secured to said wheel, a plate secured to said axle adjacent to the wheel, arms pivoted on said plate, a pinion rotatably mounted in said arms and meshing with said gear, a pair of toggles mounted on said plate, a clutch shoe carried by said toggles, a plate secured to said first mentioned plate and spaced therefrom for guiding said toggles, a wedge passing through said first mentioned plate and engaging said toggles, a platen rotating knob secured to the platen axle, and means projecting outwardly from said knob, and connected to said wedge for operating the same.

12. In a typewriting machine, a platen axle, a line-space wheel, a gear secured to said wheel, a pinion meshing with the gear, a peripherally grooved friction wheel or disk secured to the pinion, a wedge faced clutch shoe movable into and out of engagement with the friction disk, and toggle mechanism for actuating the shoe.

13. In a typewriting machine, a platen axle, a line-space wheel, a gear secured to

said wheel, a pinion radially movable with respect to the gear and yieldably held to mesh therewith, a peripherally grooved friction wheel or disk secured to the pinion, a wedge faced clutch shoe movable into and out of engagement with the friction wheel, and toggle mechanism for actuating the shoe.

14. In a typewriting machine, the combination of a platen axle, a platen secured thereto, a line-space wheel, an annular gear secured to said wheel, a pinion within said gear and movable into tight or loose mesh with the gear, said pinion being eccentrically connected to the platen axle, and means movable into and out of clutching connection with said pinion, said means also moving said pinion bodily into tight mesh with said gear.

15. In a typewriting machine, the combination of a platen, a line-space wheel, a gear secured to said wheel, a pinion meshing with the gear, a friction wheel or disk secured to the pinion, a clutch shoe movable into and out of engagement with said disk, and means to actuate said shoe.

16. In a typewriting machine, the combination with a platen and a line-space wheel, of a train of connections connecting them and comprising a gear, a pinion in mesh with the gear, a friction disk secured to the pinion, and a clutch shoe movable into and out of engagement with the disk.

17. In a typewriting machine, the combination with a platen and a line-space wheel, of a train connecting them and comprising an internal gear, a pinion in mesh with the gear, a friction disk carried by and concentric with said pinion, a clutch shoe co-operating with said friction disk, and means to operate said shoe.

18. In a typewriting machine, the combination with a platen and a line-space wheel, of means connecting them and comprising an annular gear, a pinion meshing therewith, means connected with said pinion and forming a clutch surface, a co-operating clutch member, and mechanism to move the latter into and out of engagement with said clutch surface.

19. In a typewriting machine, the combination with a platen axle, of a line-space wheel loose thereon, an internally toothed gear connected to the line-space wheel, a pinion meshing with said gear, a swinging member carrying said pinion and pivoted eccentrically of the platen axle to a member rotating with the axle, and friction mechanism for holding the pinion against rotation on its axis.

20. In a typewriting machine, the combination with a platen axle, of a line-space wheel loose thereon, an internally toothed gear connected to the line-space wheel, a pinion meshing with said gear, a swinging member carrying said pinion and pivoted

eccentrically of the platen axle to a member rotating with the axle, a friction disk carried by said pinion, a brake shoe, and mechanism to move the brake shoe into and 5 out of engagement with said friction disk.

21. In a typewriting machine, the combination with a platen and a line-space wheel, of means connecting them and comprising 10 an annular gear, a pinion in mesh with said gear and movable in a substantially radial direction, a friction disk carried by said pinion, a brake shoe movable in a substantially radial direction to grip said disk and also to jam the pinion against the annular 15 gear, and mechanism to operate the brake shoe.

22. In a typewriting machine, the combination with a platen axle, a platen secured thereto and a line-space wheel loose on the 20 axle, of an annular gear carried by the line-space wheel, a plate fixed to the platen axle, a pinion in mesh with the annular gear, arms carrying said pinion and pivoted to said plate eccentrically of the axle, a friction disk carried by said pinion, a brake 25 shoe, toggles connecting the brake shoe and said plate, and a wedge for actuating the toggles.

23. In a typewriting machine, the combina-

tion with a platen and a line-space wheel, of 30 a connecting train comprising an intermeshing gear and pinion, a friction disk secured to said pinion, a clutch shoe movable into and out of engagement with said disk, and means to operate said shoe and simultaneously force the members of said train together.

24. In a typewriting machine, the combination with a platen, of a line-space wheel, a train connecting them and comprising intermeshing gearing and a friction clutch, 40 said clutch comprising a member rotatable with a member of said gearing and an engaging member, and means to operate the latter.

25. In a typewriting machine, the combination with a platen, of a line-space wheel, a train connecting them and comprising intermeshing gearing and a friction clutch, 45 said clutch comprising a member rotatable with a member of said gearing and an engaging member, and toggle mechanism for moving the latter into and out of frictional engagement with the rotatable member.

CORNELIUS B. CORCORAN.
